UNITED STATES PATENT OFFICE.

MARION J. RICH, OF TRENTON, NEW JERSEY, ASSIGNOR TO MURRAY RUBBER COMPANY, OF TRENTON, NEW JERSEY, A CORPORATION OF NEW JERSEY.

DESIGN FOR A TIRE.

Application filed April 22, 1924. Serial No. 9,354. Term of patent 14 years.

To all whom it may concern:

Be it known that I, MARION J. RICH, a citizen of the United States, residing at Trenton, in the county of Mercer and State of New Jersey, have invented a new, original, and ornamental Design for Tires, of which the following is a specification, reference being had to the accompanying drawing, forming part thereof.

What I claim is:—
The ornamental design for a tire, as shown.

MARION J. RICH.
